[57] CLAIM

The ornamental design for a combined underwater
treadmill and station therefor, as shown and described.

DESCRIPTION

FIG. 1 is a top perspective view of a combined under-
water treadmill and station therefor showing our new
design;

FIG. 2 is a front elevational view thereof;

FIG. 3 is a side elevational view thereof taken from the
right of FIG. 2;

FIG. 4 is a side elevational view thereof taken from the
left of FIG. 2;

FIG. 5 is a top plan view thereof;

FIG. 6 is a bottom plan view thereof; and

FIG. 7 is a rear elevational view thereof.
